UNITED STATES PATENT OFFICE.

FRANK X. SCHNEIDER, OF HELENA, MONTANA.

COMBINED JOINING AND FRAYING MACHINE.

Application filed December 17, 1923. Serial No. 681,223.

To all whom it may concern:

Be it known that I, FRANK X. SCHNEIDER, a citizen of the United States, residing at Helena, in the county of Lewis and Clark 5 and State of Montana, have invented certain new and useful Improvements in a Combined Joining and Fraying Machine, of which the following is a specification.

This invention relates to an improved 10 joining and fraying machine particularly adapted for use in the manufacture of fluff rugs. In the present manufacture of what are known as fluff rugs, it is customary to utilize old carpets which have first been cut 15 into strips of various lengths and then connected by sewing or in any other suitable manner, providing a continuous strip, which is passed through what is known as a fraying or ravelling machine, which severs the 20 warp threads upon opposite sides of the center of the strip, leaving the warp threads in the center of the strip intact. In this method, only fairly good carpets can be used, as old or worn carpets will tear apart in the 25 frayer or raveller.

It is the main object of my invention to provide a combined joining and ravelling machine, whereby the various lengths of carpet may be passed through the machine with 30 the ends of the strips overlapping one another and while the strip is passing through the machine a cord fed upon opposite sides of the strip so that after the strips have passed through the fraying machine and the 35 majority of the warp threads cut and then passed into the twisting machine, the cords which are disposed upon opposite sides of each of the strips will hold the woof threads together, and prevent any displacement 40 thereof while passing through the fraying machine and also provide for a strengthening of the strip after being twisted.

Another object of the present invention is the provision of an improved joining and 45 fraying machine wherein the strips of carpets which are cut in various lengths may be readily fed into the machine with the ends in overlapping relation and the warp threads upon opposite sides of the center of the strip 50 readily severed at intervals and wherein no extraordinary strain is placed upon the remaining warp threads which are left intact which will lessen the liability of accidental 55 ripping or tearing of the strips as they are passed through the machine.

A further object of the present invention

is the provision of a combined joining and fraying machine of the above character, wherein the strips of carpet are readily guided between the presser roll and the cutting knives so that the warp threads will be readily severed to the proper width upon opposite sides of the center of the strip and leave a sufficient number of warp threads in the center of the strip to retain the strip intact and prevent the same from being ripped or torn apart.

A still further object of the invention is the provision of a machine of this character, wherein means is provided for feeding strengthening cords to opposite sides of the strip while being fed through the machine, so that when the proper number of warp threads have been severed, the strengthening cords will be placed in position upon opposite sides of the strip for retaining the woof threads against displacement should the remaining threads in the center of the strip become broken while being passed thru the fraying machine, so that when the strip passes from the fraying machine, ready to be fed into the twisting machine, any displacement on the part of the woof threads is eliminated.

With the above and other objects in view, the invention consists in the novel features of construction, the combination and arrangement of parts as will be hereinafter more fully set forth, pointed out in the claims and shown in the accompanying drawings, in which:

Figure 1 is a side elevation of my improved joining and ravelling machine.

Figure 2 is a similar view, part of the device being broken away and illustrated in cross section.

Figure 3 is a rear elevation of the machine.

Figure 4 is a top plan view.

Figure 5 is a detail longitudinal sectional view, taken through the cutting mechanism.

Figure 6 is a detail plan view of a strip of carpet showing the warp threads intact before being passed through my improved machine.

Figure 7 is a similar view, showing the manner in which the warp threads are cut, after being passed through the machine, and

Figure 8 is a plan view illustrating the relative positions of the reinforcing cords after the strip has been passed through the

twisting machine, illustrating how the woof threads are held in position, should any of the remaining warp threads become broken.

5 Referring now more particularly to the drawings, wherein various reference characters are used to designate the several parts throughout the views, A indicates the frame which supports my improved machine, said 10 machine including the feeding mechanism B and the cutting and joining mechanism C, the latter including in its construction the means for feeding the strengthening cords to opposite sides of the strip as it is 15 passed through the machine.

The frame A includes in its construction a supporting table for the feeding mechanism. This table for the feeding mechanism comprises a plurality of uprights 1, 20 suitably connected by the longitudinal pieces 2 and the transverse members 3. Mounted upon the top of the frame is a platform 4, which may be utilized for supporting a number of the strips prior to being 25 fed into the machine, the ends of said platform being recessed to permit the rotation of the pulleys 5 and 5' which are mounted upon the transverse shafts 6, said shafts having their ends mounted within 30 the uprights 1.

The feeding mechanism in general consists of the pulleys 5 and 5' over which is passed the belt 7 and mounted upon the belt 7 are the guide trays 8 which are preferably of a width to accommodate various widths of strips which are to be fed into the machine. Attention is directed to the fact that these trays 8 are loosely connected to the belt 7, so that they may readily pass 35 around the pulleys 5 and 5'. In order to carry the strips into the cutting machine when being placed within the trays 8, a conveyor belt 9 is arranged within the trays 8, and in order to provide for positive feeding 40 of the strips into the cutting machine, the conveyor belt 9 passes around the guide pulley 10, which is arranged in close proximity to the cutting mechanism, so as to carry the strips of material as close to the cutting 45 mechanism as possible in order to insure the positive feeding of the same thereto.

The guide pulley 10 is supported upon a bracket 11, which is carried by the frame 8 and is arranged within the transverse opening formed in the bottom of the guide member 11, whereby it will be noted that when the conveyor belt reaches the forward end of the feeding mechanism, it is passed 50 around the pulley 10, so as to carry the strips of material as close to the cutting mechanism as possible, and after passing around the pulley 10 is guided back into the tray members 8.

65 It will be noted that two of the uprights which comprise the supporting frame for

the feeding mechanism extend upwardly above the platform, as shown at 12, and mounted at the upper ends of these extended portions are suitable bearings 13 in which the ends of the shaft 14 are mounted. 70 This shaft 14 supports the pulley 15 and also supports the arms 16 which are loosely mounted upon the shaft and support at their outer ends guide pulleys. Both of the pulleys 15 and 17 are grooved to receive a belt 18, which passes around the pulleys and is arranged in close proximity to the conveyor belt 9, so that when the strips of material are fed onto the conveyor belt and toward the cutting mechanism, the belt 18 75 will contact with the upper face of the strips holding the same against longitudinal movement on the belt 9, so that when the strips are fed toward the cutting machine with their ends in overlapped relation, the belt 18, together with the pulley 17 will retain the ends of the strips in their proper positions when being fed into the cutting mechanisms. Attention is called to the fact that as the arms 16 are loosely mounted upon the shaft 14, the weight of the pulley 17 tending to bear constantly upon the upper face of the strips of material will retain the material against movement so that the same will be fed into the cutting mechanism in its proper position to have the number of warp threads cut upon opposite sides of the center of the strip.

The main portion of the frame A supports the cutting mechanism and includes a platform 19 having upon its upper face the spaced bearing sockets 20 and extending upwardly from these sockets are the threaded supporting posts 21. The bearing sockets 20 are connected by means of the longitudinal beams 22, each having the spaced transverse openings 23 therethrough for the reception of the operating shafts 24, and 24'. Mounted upon the outer end of the shaft 24' is the drive pulley 25, which is connected by means of a belt 26 to any suitable source of power which may be utilized for driving the machine. The shaft 24' also supports a gear 27, which is mounted upon the shaft and arranged between the pulley 25 and one of the longitudinal beams 22 as clearly illustrated in Figure 4. The shaft 24 has mounted upon one end thereof the gear 28. Supported upon the upright post 21 and arranged in spaced relation with the beams 22 are a second set of beams 29, which are arranged in spaced parallel relation as shown in Figure 4 and each of these beams 29 is provided with an opening 80 to receive the threaded post 21, said beams being retained in position above the beams 22 by means of the nuts 30, which are threaded onto the post 21 and arranged upon opposite sides of the beams 29.

85 The beams 29 are provided with aligned

bearing openings, in which the shaft 31 is mounted, one end of said shaft supporting a gear 32, which is adapted to mesh with the gears 27 and 28, and from this it will be apparent that as the gear 27 is driven through the medium of the pulley 25 and belt 26, it will impart movement to the gear 28 through the gear 32, so that the shafts 24, 24' and 31 will be driven simultaneously.

Mounted upon the end of the shaft 31 opposite the gear 32 is the pressure disc 23, said disc being retained upon the end of the shaft by having the end of the shaft threaded and a nut 34 mounted upon the threaded portion adapted to be screwed firmly against the face of the disc to retain the same in position upon the end of the shaft.

Attention is particularly directed to the fact that the ends of the shafts 24 and 24' opposite the gears 27 and 28 are provided with reduced portions 35 and 35' and mounted upon these reduced portions 35 and 35' are the cutting discs 36. These discs 36 are provided upon their peripheries with the cutting edges 37 which are arranged in circumferential spaced relation and are so arranged with respect to the disc 33 that during the rotation of the disc 33 and the disc 36, the cutting edges 37 will consecutively engage the periphery of the disc 33. The discs 36 are keyed to the ends of the shafts 24 and 24' and adapted to rotate therewith and are retained in spaced relation by means of a spacing plate 38. This plate 38 is provided with transverse bearing openings arranged in spaced relation and mounted within these bearing openings are the sleeves 39, which are loosely mounted upon the shafts 35 and 35' and attention is directed to the fact that these bearing sleeves are fitted within the openings in the plate 38 so that the ends of the sleeves 39 will project beyond the side faces of the plate and engage the faces of the disc 36, to prevent frictional contact between the plate 38 and the disc 36.

Arranged upon opposite sides of each pair of discs 36 are the guide plates 40, each of said guide plates being provided with spaced openings and mounted within these openings are the bearing sleeves 41, the ends of which project beyond the side faces of the plates 40 so that there will be no frictional contact between the discs 36 and the plates 40. The forward ends of the plates 40 are each provided with a cut-away portion adapted to be bent outwardly as shown at 42 so as to guide the strip onto the discs 36 after its passage through the guide member 11, and in order to retain the strips in place while being passed from the first set of cutting discs to the second set of cutting discs, the plates 40 are provided

intermediate their ends with struck out portions 43 which will assist in guiding the strip while being passed from one set of discs to the other so that the strip will be retained in its proper relative position with respect to the cutting discs and the pressure bearing disc 33.

As a general rule, when the strips pass through a cutting or fraying machine, the warp threads which are left intact in the central portion of the strip for retaining the woof threads in place become broken or torn apart and in order to retain the woof threads in their proper position and prevent displacement of the same, I have provided an improved means for feeding strengthening cords to opposite sides of the strip of material by means of said cutting mechanism which when the strip is twisted will prevent displacement of the woof threads, and in order to carry this out, a supporting bracket 44 is mounted upon this portion of the frame and is adapted to support the spool 45 upon which the cord has been previously wound and as the cord passes from the spool 45, it is extended through a guide 46, which directs the cord into the groove 47 formed in the periphery of the disc 23. This groove 47 will guide the cord 48 onto the upper face of the strip as it is being fed through the cutting mechanism.

Arranged below the discs 36 is a bracket 49 which supports a spool 50 upon which the cord 51 has been previously wound, the cord of this spool extending through the guide 52 and then upwardly around the forward end of the plate 38. It will be noted that the forward end of the plate 38 is provided with a groove 53 forming a continuation of the groove 53 which is formed in the upper face of the plate 38. From this it will be noted that the cord 51 is fed through the cutting mechanism with the strip so that the same will be arranged upon the lower face of the strip and in opposed relation to the cord 48, the cord 51 passing through the groove 53 in the upper edge of the plate 38 so as to retain the same in its proper position with respect to the strip being fed through the cutting mechanism.

Each end of the brackets 44 and 49 have mounted thereon the tension springs 54 which are retained in position against the ends of the spool by means of the thumb nuts 55 whereby the tension of the springs 54 may be adjusted to regulate the feed of the cords 48 and 51. In order to impart movement to the feeding mechanism, the pulley 57 located at the forward end of the feeding mechanism and adjacent the cutting mechanism is provided with an extended face portion over which a belt 56 passes, said belt extending around a pulley 57 mounted upon the outer end of the shaft

24'. From this it will be apparent that the feeding mechanism is operated simultaneously with the cutting mechanism.

From the above description, it will be readily apparent that after the old carpets have been cut into strips of various lengths, they may be readily placed within the trays 8 upon the conveyor belt 9 with their ends in overlapped relation and through movement of the conveyor belt will be fed through the guide 11' onto the first set of discs 36, the plate 40 retaining the strip against lateral movement so that when the same passes between the discs 33 and the first set of discs 36, the proper number of warp threads will be severed upon opposite sides of the center of the strip and the rods 38 and 41 threaded through the machine upon opposite sides of the strip. As the strip leaves the first set of cutting discs, it is guided by the plate 40 between the second set of cutting discs and the disc 33 so that the side warp threads may be further cut to provide for the separation of the ends of the woof threads in each strip, leaving only the central warp threads intact. In a great many instances, these warp threads which remain intact in the center are not sufficiently strong to retain the woof threads in their respective position, and it is the object of feeding the cords 48 and 51 on opposite sides of the strip to retain these woof threads in their respective positions and should any of the remaining warp threads become broken by passing through the cutting mechanism.

In the construction of my improved machine, it is preferred to have the disc 33 formed of comparatively soft material, such as soft steel or the like, so as to not upset the cutting edges 37 on the discs 36 which contact with the periphery of the disc 33 and it will be noted from this that through constant contact of the cutting edges 37 with the periphery of the disc 33, a continual wear upon the periphery of the disc 33 will be carried on through the engagement of the cutting edges 37 with the disc. In order to compensate for this wear upon the periphery of the disc 33, the shaft 31 may be slightly adjusted in a vertical plane through the adjustment of the nuts 30 arranged upon opposite sides of the supporting beams 29, which are mounted upon the upright threaded posts 21. It will be understood that this adjustment of the shaft 31 is comparatively slight so as not to interfere with the continual engagement of the gears 27, 28 and 32. Through this adjustment, the slight wear upon the periphery of the disc 33 will be well taken care of, so that the proper amount of pressure between the disc 33 and the discs 36 will be arranged for so as to positively sever the warp threads along the sides of the strips by

being passed through the cutting mechanism. In Figure 6 I have shown a plan view of the strip of old carpet wherein the warp threads are intact and the strip is in position to be inserted in the cutting mechanism. In Figure 7 a plan view of the strip is illustrated, showing the position of the strip after being passed through the first set of discs 36, illustrating a number of the warp threads upon the opposite sides of the center of the strip in severed position and it will be apparent that after this strip has been passed over the second set of cutting discs 36, the remaining portions of the side warp thread will be severed so as to leave the ends of the woof threads entirely separated.

In Figure 8 I have illustrated a plan view of the fluff after the same has been twisted, prior to weaving a new rug. In this view, it will be noted that the cords 48 and 51 which are arranged upon opposite sides of these strips are twisted with the strip so that when the strip lies flat, as illustrated in this figure, the cords will be alternately arranged upon opposite faces of the sections 58 of the strip and by having the cords arranged in this manner, they will be retained in a comparatively taut condition so as to eliminate any displacement on the part of the woof threads while the strips are being woven.

By the use of my improved combined joining and ravelling machine, attention is directed to the fact that considerable time and labor is thus saved in forming the strips ready to be woven into what are known as fluff rugs. Heretofore the strips had to be sewed together by hand into a continuous long strip prior to the insertion into the ravelling or cutting machine, and no means has heretofore been provided for reinforcing or strengthening the strip prior to its passage into the twisting machine, so that considerable material has been wasted heretofore, due to the fact that in a great many instances the carpets from which the strips were cut were too old and worn to stand the strain while being passed through the ravelling machine, but with my improved machine, and method of strengthening or reinforcing the strip, all types of old carpet or worn carpet may be utilized with very little danger of the tearing apart of the strips while being passed through the machine.

In the illustrations in Figure 6, attention is called to the fact that for the purpose of clearly illustrating the various positions of the warp and woof threads, the warp threads 59 extend alternately upon opposite sides of the woof threads 60, and the woof threads 60 are spaced at intervals, this spacing usually taking place while the warp threads 59 are being severed by the cutting

discs 36. It will be noted the cutting edges 37 are substantially pyramidal in shape so that as the strip passes between the disc 33 and the cutting discs, the cutting edges will 5 pass between the woof threads and separate them to a certain extent so that when the strip is passed through the twisting machine and twisted as shown in Figure 8, the loose ends of the woof threads will form a comparatively fluffy strip which when woven into rugs and the like form what are known as fluff rugs.

In order to provide for the proper tension in the feeding of the strip, it will be noted 15 that the belt 18 and pulley 15 exert a pressure upon the upper face of the strip while being fed to the cutting machine so that the strip will be evenly fed between the discs 33 and 36, and by having the tension springs 20 54 bearing against the ends of the spools 45 and 50, the cords 48 and 51 will be fed onto opposite sides of the strip at an even tension so that when the strip leaves the cutting machine with the side warp threads severed, 25 the reinforcing cords 48 and 51 will retain the woof threads in their respective positions providing any of the remaining or intact warp threads become broken, so that the strip may be readily passed into the twisting 30 machine for twisting into the form as illustrated in Figure 8.

While I have shown and described the preferred form of my invention, I wish it to be understood that various changes and alterations may be carried out without departing from the spirit of the invention or the scope of the appended claims, in which—

I claim:

1. A machine of the class described including a supporting frame, a pressure disc mounted for rotation upon the frame, spaced cutting discs adapted to engage the periphery of the pressure disc in spaced relation axially thereof, and means for feeding strips of material between the pressure and cutting discs.

2. A machine of the class described including a supporting frame, a pressure bearing disc rotatably mounted upon the frame, 50 spaced cutting discs carried by the frame for engagement with the periphery of the first disc, in spaced relation axially thereof, means for feeding strips of material between said discs, and additional means for feeding a reinforcing cord to opposite sides of the strip while being passed between said discs.

3. A machine of the class described including a supporting frame, spaced shafts 60 mounted thereon, a gear upon one end of each of said shafts, a drive pulley upon one of said shafts adjacent the gear, spaced cutting discs mounted upon the ends of the shafts opposite the gears, a third shaft arranged above and intermediate the spaced

shafts, a gear carried by one end of the third shaft meshing with the gears on the first mentioned shafts, and a pressure bearing disc mounted upon the other end of the third shaft opposite the gear and having 70 a contacting relation with the cutting discs.

4. A machine of the class described including a supporting frame, a pressure bearing disc mounted for rotation upon the frame, spaced cutting discs adapted to engage the periphery of the pressure bearing disc in spaced relation axially thereof, and means for adjusting the pressure bearing disc toward and away from the cutting discs.

5. A machine of the class described including a supporting frame, a pressure bearing disc mounted for rotation upon the frame having an annular groove in its periphery, spaced cutting discs adapted to engage the periphery of the first disc upon opposite 85 sides of the groove, a spacing plate arranged between said discs and having a groove in its upper edge, cord supporting elements arranged below the cutting discs and above the bearing discs, and means for guiding the cords into the groove in the bearing discs and into the groove in the upper edge of the spacing plate.

6. A machine of the class described including a supporting frame, a pressure bearing disc rotatably mounted upon the frame having an annular groove in its periphery, spaced bearing discs arranged in pairs beneath the bearing discs for engagement with the periphery thereof upon opposite sides of the annular groove, a spacing plate arranged between said discs having a groove in its upper edge, means for feeding strips of material between said discs, and additional means for feeding reinforcing cords into 100 the grooves in the spacing plate and bearing discs whereby to dispose the reinforcing cord upon opposite sides of the strip while being passed between said discs.

7. A machine of the class described including feeding mechanism, comprising spaced pulleys, a belt movable over the pulleys, guide trays carried by said belt, a second pulley in the guide trays, and a movable pressure member arranged above the feeding mechanism and movable simultaneously with the second belt during the passage of material between the pressure member and the second belt.

8. A machine of the class described including a supporting frame, upright threaded posts arranged in spaced relation upon the frame, supporting beams mounted upon said posts and arranged in superposed spaced relation, spaced shafts mounted in the lowermost beams, driving means connected with one of said shafts, a third shaft carried by the uppermost spaced beams, driving connection between the first two shafts and the third shaft, a pressure bearing disc carried 120 125 130

6
by the third shaft, spaced cutting discs carried by the first mentioned shafts and contacting with the periphery of the bearing disc, and means for adjusting the third shaft 5 for moving the bearing disc toward and away from the cutting discs.

9. A machine of the class described including a supporting frame, cutting discs arranged in spaced pairs at one side of the 10 frame, a bearing disc mounted above the cutting discs and having its periphery contacting with the cutting discs, means for driving the cutting and bearing discs, supporting members arranged above the bearing 15 discs and below the cutting discs, a spool of cord mounted upon each of said supporting members, guide members arranged adjacent the spools of cord, means for feeding a strip of material between the cutting discs and bearing disc, and means for guiding the cord from each of said spools to opposite sides of the strip of material while being passed between the discs and means for regulating the feeding tension of said cords.

25. 10. A machine of the class described including feeding mechanism, comprising spaced pulleys, a belt movable over the pulleys, guide trays carried by said belt, a guide trough arranged adjacent one of said pulleys, a guide pulley carried by said trough, a second belt mounted within the guide trays and movable over the guide pulley in the trough, and a movable pressure member arranged above the feeding mechanism in close 30 proximity to the second belt.

11. A machine of the class described including a supporting frame, a pressure bearing disc rotatably mounted upon the frame, cutting discs carried by the frame and adapted to contact with the periphery of the bearing disc, said cutting discs being arranged in 40 pairs disposed in alignment with one another, the discs of each pair being arranged in spaced relation, transverse cutting edges spaced apart annularly around the periphery of the discs, means for feeding a strip of material between the cutting discs and the bearing disc, and additional means for feeding a reinforcing cord to opposite sides 45

of the strip while being passed between said 50 discs.

12. A machine of the class described including a supporting frame, spaced cutting discs carried by said frame, a bearing disc arranged above the cutting discs and adapted to contact therewith, means for feeding a strip of material between said discs, means for regulating the feed of the strip of material, means for adjusting the bearing disc toward and away from the cutting disc, and 60 means for feeding a reinforcing cord to opposite sides of the strip while being passed between said discs.

13. A machine of the class described including a supporting frame, a pressure disc 65 mounted for rotation upon the frame, spaced cutting discs adapted to engage the periphery of the pressure disc, means for feeding a strip of material between said discs, means for feeding a reinforcing cord to opposite 70 sides of the strip while being passed between said discs, and means for regulating the tension of said reinforcing cords while being fed to opposite sides of the strip of material.

14. A machine of the class described including a supporting frame, a pressure disc mounted for rotation upon the frame, spaced cutting discs adapted to engage the periphery of the pressure disc in spaced relation 75 axially thereof, means for feeding a strip of material between said discs, means for guiding the strip of material in its proper relative position with respect to the cutting discs and bearing disc, and means for regulating the pressure between the cutting discs and 80 the bearing disc.

15. A machine of the class described including spaced cutting discs, a bearing disc, mounted to have its periphery contacting with the cutting discs, means for feeding a 90 strip of material between said discs, means for feeding a reinforcing cord to opposite sides of the strip while being passed between said discs, and means for regulating the pressure between the cutting discs and 95 bearing discs for the purpose set forth.

FRANK X. SCHNEIDER.
